UNITED STATES PATENT OFFICE.

HENRY B. KOPF, OF NEW HAVEN, CONNECTICUT.

MEANS FOR PACKING FRESH PINEAPPLES.

1,042,928.

Specification of Letters Patent.

Patented Oct. 29, 1912.

Application filed July 13, 1912. Serial No. 709,231.

To all whom it may concern:

Be it known that I, HENRY B. KOPF, a citizen of the United States, and a resident of New Haven, in the county of New Haven and State of Connecticut, have invented a new and Improved Means for Packing Fresh Pineapples, of which the following is a full, clear, and exact description.

This invention relates to means for packing perishable fruit in a tropical or semi-tropical climate where it is grown, preparatory to shipment to temperate climates for consumption.

The invention has particular reference to means or method of packing fresh pineapples which may have become substantially ripe before being gathered, whereby they may be shipped with safety and whereby the highest market prices are attainable. The ordinary practice in the packing and shipping of pineapples is to pull them green and to pack them more or less promiscuously in crates, each pineapple being subjected to the damaging contact between it and other pineapples or the walls of the crate. It is well known that fruit gathered green is not so wholesome and by no means of so delicious a flavor as the same fruit would be if allowed to remain undisturbed until substantially ripe.

The invention consists of the details of construction hereinafter fully described and claimed and illustrated in the drawings accompanying this specification in which like characters of reference indicate corresponding parts in all the views, and in which—

Figure 1 is a vertical section of a carton with a pineapple secured therein; Fig. 2 is a plan view of the same, the pineapple being omitted; Fig. 3 is a perspective view showing a slight modification; Fig. 4 is a detail of one of the resilient packing members of Fig. 3; Fig. 5 is a sectional detail of a modified form of the means for supporting the butt end of the pineapple; and Fig. 6 is a detail of the cup of Fig. 5.

In the practical operation of this invention, which is designed for the packing and shipping particularly of the highest grades of fruit, the pineapples are allowed to remain on the stalks until they are fully matured and show at least for a short distance from the butt end a tint indicating that they are substantially ripe. They are then cut from the stalks, leaving a projecting stem S which, due to the nature of the pineapple,

is sufficiently rigid to support the major portion of the weight thereof.

Each pineapple is inclosed in a wrapper of any suitable design or construction, preferably in the nature of a rectangular carton 10 having sides 11, a bottom 12 and an open top 13. The size of the carton is preferably such as to correspond to the size of the pineapple and it will be made of any suitable material, preferably of corrugated packing paper of well known construction, the same being light, strong, cheap and protective. At 14 is shown a form of means for receiving and supporting the butt end of the 70 pineapple so as to space the same from the bottom 12 and prevent the said butt end from impinging against the sides of the carton. This means 14, as indicated in Figs. 1 and 2, comprises a comparatively flat member 15 having a central hole 15^a and a marginal rim 16. This device is adapted to substantially fit the lower portion of the carton and lie with the rim 16 in contact with the bottom 12, the plate 15 thereof being spaced 75 from the bottom 12 and through its hole 15^a is adapted to receive the aforesaid stem S. Before packing the pineapples the said stems are preferably coated by some suitable sealing material such as melted wax or 80 paraffin, whereby air is excluded from the flesh of the fruit and the stems otherwise rendered better fitted to the supporting means for the butt end of the pineapples.

In that form of the invention shown in 90 Figs. 5 and 6, the stem S is fitted into the cup 17 secured permanently and rigidly as by prongs 17' to the member 14' and adapted to contain melted sealing material indicated at P. By this means, as before, the 95 butt of the pineapple is spaced from the bottom of the carton and through the stem S is prevented from lateral vibration toward or against the walls thereof.

Any suitable form of flexible packing 100 members may be used between the crown of the pineapple and the walls of the carton for the purpose of protecting the same and thereby distribute the strain thereof due to the packing and shipment among a great 105 many different points of contact. To this end I use, as indicated in Figs. 1 and 2, a series of hollow triangular pyramidal members 18, one for each corner of the carton and adjacent the mouth thereof. These 110 members 18 also may be made of corrugated paper as above described.

The form of packing members shown in Figs. 3 and 4 consists of a plurality of resilient cylindrical devices 18' made of excelsior or the like, each wrapped with paper 19 or the like for convenience of manipulation. The rolls 18', in addition to protecting the crown or upper portion of the pineapple, may, if desired, extend all the way down to the butt, although it is not necessary in view of the projecting stem and the means for supporting the same for the crown supporting members to extend so far down.

Having thus described my invention, what I claim as new and desire to secure by Letters Patent is:—

1. In means for packing fresh ripe pineapples, the combination of a carton having a bottom, sides and open top, a cup containing sealing material within the carton and secured to the bottom to receive the pineapple stem whereby air is excluded from the pineapple and the butt is supported out of

contact with the sides of the carton, and resilient packing members between the crown 25 of the pineapple and the carton walls.

2. In means for packing fresh ripe pineapples, the combination of a carton having a bottom, sides and open top, means within the carton adjacent said bottom to receive the pineapple stem whereby the pineapple butt is supported out of contact with said bottom and prevented from impinging against the sides of the carton, and a series of hollow triangular pyramidal packing members between the crown of the pineapple and the carton walls, substantially as set forth.

In testimony whereof I have signed my name to this specification in the presence of 40 two subscribing witnesses.

HENRY B. KOPF.
